Charles E. Williams

Attorney

UNITED STATES PATENT OFFICE.

CHARLES E. WILLIAMS, OF DETROIT, MICHIGAN, ASSIGNOR TO GENERAL MOTORS CORPORATION, OF DETROIT, MICHIGAN, A CORPORATION OF DELAWARE.

CARBURETOR.

Application filed December 8, 1920. Serial No. 429,223.

This invention relates to carburetors and more particularly to carburetors of the auxiliary air valve type and has for one of its objects the provision of thermally operated means for normally controlling the operation of the auxiliary air valve so that the fuel mixture will be properly compensated to correspond to variations in the temperature of the air supplied to the carburetor.

Another object of the invention is the provision of means for securing desired automatic compensation for varying atmospheric temperatures, in combination with the usual permanent and temporary manually operated adjustments for the air valve spring.

A still further object of the invention is the provision of means whereby the desired thermostatic compensation for variations of atmospheric temperature may be equally operative in its action of varying the tension on air valve spring in proportion to temperature variations by addition to or reduction of tension already brought about by operation of either of the manually operated adjustments.

Other and further objects and advantages of the invention will appear as the description proceeds.

30 On the drawings:

Fig. 1 shows a side elevation of a carburetor, parts being shown in section and parts broken away, showing my improved valve control in position thereon.

35 Fig. 2 is a side elevation of that portion of the carburetor shown in Fig. 1 that extends laterally toward the right hand side of the drawing.

Fig. 3 is a view at right angles to that 40 shown in Fig. 2 with parts in section.

Fig. 4 is a fragmentary view showing certain elements of the carburetor in perspective.

The carburetor 1 is provided with the 45 usual float chamber or bowl 2 having the float 3 for controlling the flow of liquid fuel through the inlet valve, not shown. A nozzle 4 in communication with the float chamber at its lower end extends into a 50 strangle tube 5 which in turn is in communication with the mixing chamber 6 in which is located the throttle 7. The primary air enters the strangle tube and mixing chamber through the passage 8 about the nozzle 4. The parts thus far described are

merely by way of example in order to illustrate how my invention may be applied. It is understood that my invention may be applied to forms of carburetors other than the one shown and described.

The numeral 9 designates a lateral extension casing on the carburetor having an air passage 9' therein through which the secondary air is admitted to the mixing chamber. The air is adapted to enter the passage 9' through the port or opening 10 which is closed by any suitable means as by means of the valve or closure 11. The valve or closure 11 is adapted to open inwardly and is movably secured to the edge of the opening 10 in any suitable manner as by being provided with a downwardly extending angular arm 12 rigidly attached thereto and adapted to be pivoted to the lug 13. The arm 12 may, if desired, be provided with the usual counterweight 14 to counterbalance the weight of the valve.

70 The valve 11 is provided with suitable controlling means which automatically controls the flow of air through the passage 9'. The usual gasket 15 may be secured about the opening 10 to prevent noise or rattling which might otherwise occur on some types of engines.

75 It is well known that a proper explosive mixture depends on the amount of air supplied to the vaporized fuel and, since the mass or weight of air in any given volume varies inversely as the temperature, it follows that a thermally controlled device 80 adapted to control the flow of air to the mixing chamber will act automatically to supply the proper amount of air to said chamber under all thermal conditions about and within the same, and to maintain at 85 all times and under all temperature conditions the most efficient and effective explosive mixture.

In order to ensure the proper amount of air entering through the passage 9' to the 90 mixing chamber to make the proper explosive mixture under all thermal conditions, I have provided the valve 11 with thermally controlled means for controlling the opening movement thereof.

95 Extending transversely through the outer end of the lateral extension 9 is a rock-shaft 16 which carries a thermostat supporting member 17, said member being clamped in place upon the shaft by means of screws 18.

which extend through one end and into the body portion thereof.

A thermostatic arm or thermally controlled arm or member 19 is adapted to be secured to the member 17 in any suitable manner. As shown, one end of said member extends around the rock-shaft 16 and is secured to the supporting member 17 by means of the screws 18. The free end of the arm 10 19 is connected to the valve preferably by means of a compression spring 20 secured at one end to a lug 21 carried by the arm and at its other end it is secured to a lug 22 carried by the valve or closure 11.

15 The thermally controlled arm 19 is so constructed and arranged that as the temperature within the carburetor casing and about the same increases the arm will tend to straighten out thus relieving the compression 20 on the spring 20 and consequently rendering the valve or closure 11 more easily operated. A set screw 23 extending through the extension casing 9 is adapted to engage the free end of the member 17 to thereby adjust 25 the same, which adjustment adjusts the initial position of the element 19 and so controls the opposition of the spring 20 to opening movement of the valve 11. A detent 23 holds the screw 23 in adjusted position in the 30 usual manner.

A suitable spring 30 may be employed to maintain the free end of the member 17 in contact with the set screw 23. As shown, this spring consists of a wire loop engaging 35 the under side of the thermostatic arm 19 adjacent to its end which is attached to the holding member 17 and having its ends bent to extend over the shaft 16 and to engage beneath the ledge 31.

40 The arrangement described is such that the action of the spring 20 on the valve or closure 11 may be adjusted until the valve will open sufficiently to permit the proper amount of air to be drawn into the mixing chamber 45 to produce the proper mixture for any particular temperature conditions. After correct adjustment has once been made by use of the set screw 23, the thermally controlled arm 19 will respond to temperature variations to automatically maintain the proper 50 adjustment of the valve to insure correct mixture at all temperatures, thus doing away with the necessity for frequent seasonal readjustments usually required and insuring 55 maximum efficiency of the engine at all times.

When it is desirable to temporarily enrich the mixture, as for starting the motor when it is cold, the usual manually operated mechanism for controlling the opening of the valve is provided. One form of this means is shown in Figs. 2 and 3. An arm or lever 60 24 is pivotally mounted on the rock-shaft 16 and has a lost motion connection with said 65 shaft and with the thermostat carrying mem-

ber 17 as by being provided with a lug or projection 25 (see Fig. 2) which engages between two spaced lugs 26 and 27 on a collar 32 secured to the shaft 16. The lugs 26 and 27 are spaced apart sufficiently to permit 70 a free limited movement of rotation of said member 17, and also to prevent displacement thereof in case of slight unintentional movement of the control rod or wire. A rod or Bowden wire 28 connected to the arm 24 and 75 extending through the pivoted guide 29 extends to an operating lever, not shown, within reach of the operator. It will thus be seen that the valve 11 may be manually operated by means of the wire or rod 28 and 80 arm 24 without interfering with the automatic function of the thermally controlled arm 19. In other words, when the manually controlled mechanism is employed, it co-operates with the thermally controlled means 85 in tensioning the spring 20 to thereby control the operation of the valve 11.

In starting the engine, by manually operating the rod or Bowden wire 28, additional compression may be placed on the spring 20 90 to hold the valve 11 closed to thereby enrich the mixture. After the engine warms up the lever 24 may be moved to relieve the additional tension, and restore the valve to thermal control only. 95

It will thus be seen that by adjusting the screw 23, the proper compression may be put on the spring 20, so that the engine suction will lift the valve 11 just sufficiently to permit the proper amount of air to pass into 100 the mixing chamber to make the most efficient mixture under normal temperature conditions. Moreover, by means of the manually operated devices the action of the spring may be adjusted to meet temporary 105 thermal conditions.

The compensating action of the thermally controlled means accompanying every change of temperature, greatly reduces the usual 110 "warming up" period of the motor in that 110 the arm 19, while it is cold, puts more pressure on the spring 20, thus tending to maintain the valve 11 closed and causing a richer mixture to be delivered to the engine so that driving conditions are attained very soon 115 after the motor starts. As the temperature within the carburetor casing rises the thermostatic arm 19 expands gradually relieving the pressure on the air valve spring, thereby maintaining the mixture of fuel and air at the proper proportions throughout the entire 120 range of movement of said arm. In other words, as the temperature at the arm rises the action on the air valve spring is decreased to permit a greater volume of air 125 to enter the mixing chamber, to make the proper explosive mixture, and vice versa.

It is thought from the foregoing taken in connection with the accompanying drawings that the construction and operation of my 130

device will be apparent to those skilled in the art, and that various changes in size, shape, and proportion and minor details of construction may be made without departing from the spirit and scope of the appended claims.

What I claim is:

1. In a device of the class described, a carburetor having an air passage, a valve for said passage, a counterweight for said valve, a spring for resisting the opening of said valve, a thermostat exposed to the temperature inside the carburetor casing and operatively connected to said spring for automatically varying the resistance of the same, and mechanism associated with said thermostat and acting through said spring for manually controlling the opening of said valve, substantially as shown and described.
2. In a carburetor having a lateral extension provided with an opening thereinto, a hinged valve for said opening, a spring for resisting the opening movement of said valve, a rock-shaft secured in said extension, a clamp secured about said rock-shaft and having its free end extended, a thermostatic member extending about said rock-shaft and secured to said clamp, and having its free end attached to said spring, and means engaging the free end of said clamp for adjusting the tension of said spring, substantially as shown and described.
3. In a device of the class described, a carburetor having a main air passage and an auxiliary air passage, a valve for said auxiliary air passage, controlling means, including a spring disposed within the car-

buretor casing and a thermally controlled arm associated with said valve and acting through said spring for automatically controlling the flow of air through said auxiliary air passage, said arm compensating for all temporary and seasonal variations of temperature, means for varying the tension of said spring and manually operated means acting through said spring for varying the resistance of said spring to meet temporary requirements of engine operation, substantially as shown and described.

4. In a carburetor having a main air passage and an auxiliary air passage, a valve for said auxiliary air passage, controlling means for said valve including a thermostatic arm within the carburetor casing for controlling the flow of air through said auxiliary air passage, means for adjusting said arm, a lever having a lost motion connection with said controlling means, and manually operated means connected to said lever for controlling said valve independently of said controlling means, substantially as shown and described.

5. In a carburetor having an air passage, a valve for said passage, a spring secured to said valve to close the same, thermostatic means connected to said spring, a second spring acting upon said thermostatic means and tending to move the same in one direction, and means for adjusting said thermostatic means against the action of said second spring, substantially as shown and described.

In testimony whereof I affix my signature.

CHARLES E. WILLIAMS.
